(57) **CLAIM**

We claim the ornamental design for a liquid level indicator, as shown and described.

DESCRIPTION

FIG. 1 illustrates a perspective view of the liquid level in a liquid container.

FIG. 2 illustrates perspective view of the liquid level indicator, in accordance with an embodiment.

FIG. 3 illustrates a top view of the liquid level indicator.

FIG. 4 illustrates a bottom view of the liquid level indicator.

FIG. 5 illustrates a right view of the liquid level indicator.

FIG. 6 illustrates a back view of the liquid level indicator.

FIG. 7 illustrates a left view of the liquid level indicator; and,

FIG. 8 illustrates a front view of the liquid level indicator.

1 Claim, 4 Drawing Sheets
